J. V. HENLEY.

CARBURETER.

APPLICATION FILED APR. 16, 1915.

1,169,483.

Patented Jan. 25, 1916.

Inventor:

Joseph V. Henley,

By Hugh H. Wagner,
his Attorney.

UNITED STATES PATENT OFFICE.

JOSEPH V. HENLEY, OF ST. LOUIS, MISSOURI.

CARBURETER.

1,169,483.

Specification of Letters Patent. Patented Jan. 25, 1916.

Application filed April 16, 1915. Serial No. 21,681.

To all whom it may concern:

Be it known that I, JOSEPH V. HENLEY, a citizen of the United States, residing in the city of St. Louis and State of Missouri, 5 have invented certain new and useful Improvements in Carbureters, of which the following is a specification.

This invention relates to improvements in carbureters which are particularly adapted 10 for use to control the supply of fuel and air to and the mixing of same for internal combustion engines, and has for its object to provide an improved carbureter which is so designed that it will insure the proper mixing 15 of fuel and air and effect the proper proportioning of same for the requirements for all speeds and changes in temperature and altitude.

Further, the present invention consists of 20 the novel features of construction and arrangement of parts hereinafter more fully described and pointed out in the claims.

In the accompanying drawings forming part of this specification, in which like numbers of reference denote like parts wherever they occur, Figure 1 is a vertical sectional view of a carbureter embodying the present invention; Fig. 2 is a horizontal sectional view on the line 2—2, Fig. 1; and Fig. 3 is 30 a fragmentary sectional view on the line 3—3, Fig. 1.

The casing 1 is preferably formed with a cylindrical configuration, and has an intake pipe 2 extending outwardly from one side 35 thereof and an outlet pipe 3 extending upwardly from the top of same, said outlet pipe bearing a flange 4, which is adapted to be secured to the manifold (not shown). A hollow member 5 adapted to form a finely 40 perforated lateral wall for mixing chamber 6 within casing 1 is preferably cylindrical in shape and is open at both ends, said member being preferably of wire-mesh construction and having one end adapted to be 45ipherally secured to a portion of the inner wall of the inner end of said outlet pipe 3 by any suitable means, such, for instance, as by means of solder, said end of said member being adapted to open into said outlet pipe. 50 The other end of said member may be adapted to rest upon the inner surface of the bottom of casing 1, and secured thereto, said mixing chamber 6 surrounded by said member 5 forming the perforated wall thereof being 55 adapted to extend substantially from the

top to the bottom of said casing, leaving a lateral space 7 into which space the intake pipe 2 opens. Air entering space 7 through intake pipe 2 flows into mixing chamber 6 through the perforations of member 5 60 whereby said air is broken up into fine currents and particles thus facilitating its mixture with atomized fuel thrown into said chamber and against the inner wall thereof. The intake pipe 2 may be adapted to be connected by any suitable means to a suitable receptacle (not shown) which communicates with the outer atmosphere and has its interior heated by the exhaust pipe (not shown) or other suitable means, so that 65 heated air will be drawn into the mixing chamber 6.

A butterfly compensating valve 8, which is located in the intake pipe 2 to control the passage of air into the mixing chamber 6, 75 is secured to a rod 9 that extends transversely through said intake pipe and is revolvably supported in openings in a pair of oppositely-disposed lugs 10 borne thereby. A butterfly throttle valve 11 is secured to 80 rod 12 and is located in the outlet pipe 3 to control the passage of the mixture of fuel and air from the mixing chamber 6 into the manifold, said compensating valve and said throttle-valve being preferably operatively 85 connected by mechanism (not shown) more particularly described in my prior application for patent filed November 28, 1913, Serial No. 803,479, and there being, also, provided means (not shown) so that the throttle-valve and the compensating valve may be controlled from the driver's seat of an automobile or the like, said compensating valve, said means, said throttle-valve, and the parts associated therewith being preferably 90 constructed, arranged, and operated as more particularly described and shown in my said prior application for patent.

A hollow member 13, open at both ends, has one end adapted to be supported in an appropriate opening 14, and is borne by the bottom of casing 1 by means of screw threads as shown in Fig. 1 or by any other suitable means, said opening 14 being preferably centrally located in the space marked off on the bottom of said casing by the perforated wall of the mixing chamber 6, the other end of said hollow member being adapted to extend downwardly through an opening in the bottom of a fuel receptacle 110

or cup 15 and bears lateral flange 16, which extends along the outside of the bottom of said receptacle and which is adapted to support said receptacle, the latter being preferably cylindrical with substantially the same diameter as casing 1 and being in contact at its rim with an annular groove formed in the lower peripheral edge of said casing.

A hollow member 17, which may be substantially E-shape in cross section as best seen in Fig. 1, is provided with a horizontal bore 18 therethrough which may be closed at both ends by means of plugs 19 or the like, there being a vertical bore 20 in each end-piece of said hollow member, said vertical bores being adapted to communicate with said horizontal bore, and, also, a vertical bore 21 is provided in the intermediate piece of said hollow member between said end-pieces thereof, said last named vertical bore being adapted, also, to communicate with said horizontal bore. If desired, a drain cock (not shown) may be substituted for one of said plugs 19, or a pair of drain cocks (not shown) may be substituted for both of said plugs.

Hollow member 17 is adapted to be secured below flange 16 by means of a pair of screw-bolts 22, each bolt being provided with an opening 23 therethrough, said bolts being adapted to extend through appropriate openings therefor in the bottom of receptacle 15, and flange 16, and being adapted to engage screw threads in the vertical bores 20 in the end-pieces of hollow member 17, said screw-bolts so applied being adapted, also, to secure the parts mentioned firmly in place in position as best seen in Fig. 1, and the openings 23 of said screw-bolts being adapted to establish communication between the inside of receptacle 15 and the bores of said hollow member 17.

The upper end of hollow member 13 is provided with a bearing 24 having a bore 45 of reduced size to that of the remainder of the hollow portion of said hollow member, in which bearing an atomizer 25 consisting of a tube having a dome-shaped top with a relatively small central opening 26 is rotatably mounted so that its dome-shaped top may extend into substantially the center of the bottom of the mixing chamber 6, as best seen in Fig. 1. The lower end of said atomizer is adapted to extend through and below the lower end of hollow member 13 and bears a knurled knob 27 which is secured to said end by any suitable means, such, for instance, as by means of solder, screw-threads, or the like, said knob having a central screw-threaded opening therethrough adapted to engage corresponding screw-threads borne by the intermediate piece of hollow member 17, thus supporting said atomizer adjustably in position on said intermediate piece 65 so that by means of turning said knurled

knob said atomizer may be adjusted in its bearing, and, by means of spring-actuated pin 28 supported in an appropriate opening therefor through one of the end-pieces of hollow member 17, said knob may be locked against movement in any set position of said atomizer, said pin having a point or end adapted releasably to engage the serrations of said knob, as best seen in Fig. 3.

A plurality of comparatively small openings 29 are provided in the side of the portion of atomizer 25 inclosed within the enlarged chamber of hollow member 13 below bearing 24, said openings being adapted to establish communication between said enlarged chamber and the interior of said atomizer so that air entering said enlarged chamber through the lower end of said hollow member 13 may flow into the interior of said atomizer. A bearing 30 is borne by the inner wall of atomizer 25 and is rigidly secured thereto by any suitable means, such for instance, as by means of solder, in the upper portion of said atomizer above openings 29 thereof and below the dome-shaped top of said atomizer, said bearing being adapted rotatably to support a comparatively slender tube or jet 31 mounted therein, which tube is adapted to have one end extending upwardly within said atomizer above said bearing 30 toward but not quite reaching opening 26 of atomizer 25, the opening of said end being in axial alignment with and slightly smaller than said opening 26, and the other end of said tube being adapted to extend downwardly below said bearing within said atomizer and being rigidly secured, in any suitable manner, in vertical bore 21 in the intermediate piece of hollow member 17, so that said tube is adapted to communicate with said bore and thence with the inside of receptacle 15 through bores 18, 20, and 23. Bearing 30 is provided with a plurality of openings or perforations 32, said perforations being adapted to establish communication between the upper and lower portions of the interior of said atomizer so that air entering said atomizer through openings 29 therein may, also, flow upwardly through perforations 32 in bearing 30 into the upper portion of said atomizer and on through opening 26 into mixing chamber 6.

By manipulating knurled knob 27, atomizer 25 may be raised or lowered with reference to the upper end of tube 31 so that said upper end of said tube may be closer to or farther away from opening 26 in the dome of said atomizer. By this arrangement, the tube 31 can be correctly adjusted for any desired vacuum in the mixing chamber in order to obtain the proper mixture of air and fuel through the atomizer for all speeds and fuels, and for all changes in temperature and altitude.

The construction and operation of the carbureter shown and described is such that a proper mixture of air and gasolene to provide a practically perfect fuel for all changes 5 in temperature and altitude will result when said carbureter is used; the expansive power of air being greater at a low temperature than at a high temperature, an adjustable atomizer is provided which may be regulated 10 to admit a proper atomized fuel through said atomizer into the mixing chamber suitable to atmospheric conditions whether of temperature or rarefied condition. Moreover, the atomizer is adapted to be automatically locked in any adjusted position by 15 means of spring-actuated pin 28 pressing its point against the serrated edge of knurled knob 27.

A float 33, which surrounds a depending 20 member 34 that is borne by casing 1 within receptacle 15, is slidably mounted on said member and is provided with mechanism 35 for controlling the flow of fuel into receptacle 15 from fuel supply pipe 36 through 25 valve-chamber 37, said float, the mechanism for controlling the flow of fuel, and the parts associated therewith being as shown in the accompanying drawings and as more particularly shown and described in my said prior 30 application for patent filed November 28, 1913, Serial No. 803,479 (Patent 1,148,898, Aug. 3, 1915). Valve-chamber 37 is preferably formed by providing a partition wall 38 vertically between the top and bottom of 35 the inside of casing 1, as best seen in Figs. 1 and 2 of the accompanying drawings, and valve-stem 39 and all other parts associated with said valve-stem and said valve-chamber are preferably constructed and arranged as 40 shown in the drawings and as more particularly shown and described in my said prior application for patent.

In operation, atomizer 25 having been adjusted in the manner hereinabove described, 45 and fuel having been admitted into receptacle 15 from whence it will flow into tube 31 through bores 23 of screws 22 and through the bores of hollow member 17 until it rises in said tube to substantially the level of the fuel 50 in said receptacle, and throttle-valve 11 and compensating-valve 8 having been properly adjusted, the suction stroke of each piston of the engine will cause a vacuum in mixing chamber 6 and space 7, whereupon atomized fuel will be drawn into said mixing chamber 55 through opening 26 in the dome of said atomizer. Air admitted into the interior of casing 1 through intake 2 will strike perforated wall 5 of mixing chamber 6 and will 60 enter said mixing chamber in fine streams or divisions through the perforations of said wall, thus facilitating the proper mixing of atomized fuel and air in said mixing chamber.

65 Various changes in the details of con-

struction and arrangement of parts may be made without departing from the nature and spirit of the present invention.

I claim:

1. In a carbureter, the combination with a 70 casing having an air-inlet, an outlet, and an opening in its bottom, and a central mixing chamber having an open top and bottom and having communication with said outlet, of a perforated wall surrounding said mixing 75 chamber, a fuel atomizer extending through said opening into the said mixing chamber, and means for removably supporting said atomizer adjustably in place.

2. In a carbureter, the combination with a 80 casing having an air-inlet, an outlet, and an opening in its bottom, and a central mixing chamber having an open top and bottom and having communication with said outlet, of a perforated wall surrounding said mixing 85 chamber, a fuel atomizer extending through said opening into the said mixing chamber, means for removably supporting said atomizer rotatably adjustable, and means borne by the lower end of said atomizer for rotatably adjusting said atomizer.

3. In a carbureter, the combination with a 90 casing having an air-inlet, an outlet, and an opening in its bottom, and a central mixing chamber having an open top and bottom and having communication with said outlet, of a perforated wall surrounding said mixing 95 chamber, a bearing in said opening, and a fuel atomizer rotatably supported adjustably in said bearing and extending into the 100 bottom of said mixing chamber.

4. In a carbureter, the combination with a 105 casing having an air-inlet, an outlet, and an opening in its bottom, and a central mixing chamber having an open top and bottom and communicating with said outlet, of a perforated wall surrounding said mixing 110 chamber, a bearing in said opening, a hollow member borne by said bearing and having an enlarged chamber extending downwardly 115 therefrom, said chamber having an open bottom, and a fuel atomizer removably supported rotatably adjustable in said bearing, said atomizer extending upwardly into the bottom of said mixing chamber and extending 120 downwardly through said enlarged chamber, the portion of said atomizer in said enlarged chamber being perforated to establish communication from said enlarged chamber to the interior of said atomizer.

5. In a carbureter, the combination with a 125 casing having an air-inlet, an outlet, and an opening in its bottom, and a central mixing chamber having an open top and bottom and communicating with said outlet, of a perforated wall surrounding said mixing 130 chamber, a bearing in said opening, a hollow member borne by said bearing and having an enlarged chamber extending downwardly therefrom, said chamber having an open

bottom, a fuel atomizer removably supported adjustably in said bearing, the discharge end of said atomizer extending upwardly into said mixing chamber and the lower end thereof extending downwardly through said enlarged chamber, the portion of said atomizer in said enlarged chamber being perforated to establish communication from said enlarged chamber to the interior of said atomizer, a fuel receptacle supported by said hollow member, a jet located in said atomizer and having communication with said receptacle, and screw-threaded means borne by the lower end of said atomizer adapted for adjusting the discharge end of said atomizer relative to said jet.

6. In a carbureter, the combination with a casing having an air-inlet, an outlet, and an opening in its bottom, and a central mixing chamber having an open top and bottom and communicating with said outlet, of a perforated wall surrounding said mixing chamber, a bearing in said opening, a hollow member borne by said bearing and having an enlarged chamber extending downwardly therefrom, said chamber having an open bottom, a fuel atomizer removably supported rotatably adjustable in said bearing, the discharge end of said atomizer extending upwardly into said mixing chamber and the lower end thereof extending downwardly through said enlarged chamber, the portion of said atomizer in said enlarged chamber being perforated to establish communication from said enlarged chamber to the interior of said atomizer, a fuel receptacle supported by said hollow member, a jet rigidly located in said atomizer and having communication with said receptacle, a bearing secured to the inner wall of said atomizer, said bearing being adapted to support said jet to permit said atomizer to be rotated around said jet, and a screw-threaded member borne by the lower end of said atomizer adapted for adjusting the discharge end of said atomizer relative to said jet.

7. In a carbureter, the combination with a casing having an air-inlet, an outlet, and an opening in its bottom, and a central mixing chamber having an open top and bottom and communicating with said outlet, of a perforated wall surrounding said mixing chamber, a bearing in said opening, a hollow member borne by said bearing and having an enlarged chamber extending downwardly therefrom, said chamber having an open bottom, a fuel atomizer removably supported rotatably adjustable in said bearing, the discharge end of said atomizer extending upwardly into said mixing chamber and the lower end thereof extending downwardly through said enlarged chamber, the portion of said atomizer in said enlarged chamber being perforated to establish communica-

tion from said enlarged chamber to the interior of said atomizer, a fuel receptacle supported by said hollow member, a jet rigidly located in said atomizer and having communication with said receptacle, a bearing rigidly borne by the inner wall of said atomizer, said bearing being adapted to support a portion of said jet above said perforations to permit said atomizer to be rotated around said jet on said bearing, said bearing being perforated to establish communication between the upper and lower portions of the interior of said atomizer, and screw-threaded means borne by the lower end of atomizer adapted for adjusting the discharge end of said atomizer relative to said jet.

8. In a carbureter, the combination with a casing having an air-inlet, an outlet, and an opening in its bottom, and a central mixing chamber having an open top and bottom and communicating with said outlet, of a perforated wall surrounding said mixing chamber, a bearing in said opening, a hollow member borne by said bearing and having an enlarged chamber extending downwardly therefrom, said chamber having an open bottom, a fuel atomizer removably supported rotatably adjustable in said bearing, the discharge end of said atomizer extending upwardly into said mixing chamber and the lower end thereof extending downwardly through said enlarged chamber, the portion of said atomizer in said enlarged chamber being perforated to establish communication from said enlarged chamber to the interior of said atomizer, a fuel receptacle supported by said hollow member, a member supported beneath said receptacle and having a passage communicating with said receptacle, a jet located in said atomizer and rigidly supported by said member, said jet having communication with said passage, and screw-threaded means borne by the lower end of said atomizer adapted to engage a portion of said member for adjusting the discharge end of said atomizer relative to said jet.

9. In a carbureter, the combination with a casing having an air-inlet, an outlet, and an opening in its bottom, and a central mixing chamber having an open top and bottom and communicating with said outlet, of a perforated wall surrounding said mixing chamber, a hollow member borne adjacent said opening and extending downwardly below the bottom of said casing, said member having a bearing in said opening and an enlarged chamber below said bearing and an open bottom, an adjustable fuel atomizer rotatably supported in said bearing, said atomizer having its discharge end adapted to extend into said mixing chamber and its lower end adapted to extend through said enlarged chamber, the portion of said atom-

izer within said enlarged chamber being perforated to establish communication from said chamber to the interior of said atomizer, a fuel receptacle supported by said 5 hollow member, a jet rigidly located in said atomizer and having communication with said receptacle, a fuel chamber located in said casing and having connection with a fuel-supply and, also, having an outlet 10 which opens into said receptacle, a valve controlling the outlet of said fuel chamber, a float reciprocally mounted on said hollow member, and means operative by said float for actuating said valve.

In testimony whereof I hereunto affix my 15 signature in the presence of two witnesses.

JOSEPH V. HENLEY.
